HEATING APPARATUS

Marshall Arter, East Peoria, Ill.

Application November 17, 1938, Serial No. 241,057

5 Claims. (Cl. 237—63)

The invention relates to a heating apparatus and more especially to a water heating apparatus for heating buildings or the like.

The primary object of the invention is the provision of an apparatus of this character, wherein a water circulating system is heated from a furnace and the latter is utilized not only for the heating of the water but also for production of steam, being energy for an engine which drives 10 a draft element and a water circulator, the apparatus being usable both for heating and cooling service.

Another object of the invention is the provision of an apparatus of this character, wherein 15 component elements thereof are arranged so as to be compact thus occupying minimum space and proper circulation of heated water is assured and also heated air for the warming of an enclosure or enclosures, the apparatus being 20 automatic in the working thereof.

A further object of the invention is the provision of an apparatus of this character, wherein the construction thereof requires minimum attention in that the same is automatic in the 25 working thereof and minimum consumption of fuel is required with resultant maximum heating effect.

A still further object of the invention is the provision of an apparatus of this character, 30 which is comparatively simple in its construction, thoroughly reliable and efficient in operation, and inexpensive to manufacture and install.

With these and other objects in view, the invention consists in the features of construction, 35 combination and arrangement of parts as will be hereinafter more fully described, illustrated in the accompanying drawings, which disclose the preferred embodiment of the invention and pointed out in the claims hereunto appended.

40 In the accompanying drawings:

Figure 1 is an elevation partly in section of the apparatus constructed in accordance with the invention and installed for service.

Figure 2 is a side elevation partly in section of 45 the steam power unit and adjuncts.

Figure 3 is a sectional view taken vertically through Figure 2.

Figure 4 is a sectional view taken horizontally through Figure 2.

50 Figure 5 is a fragmentary top plan view of the structure shown in Figure 2.

Similar reference characters indicate corresponding parts throughout the several views in the drawings.

55 Referring to the drawings in detail, A design-

nates generally a furnace, being of the firebox water-jacketed type, its water jacket being indicated at 10 and this furnace A is located beneath a group of rooms, portions thereof being indicated at B, of a building or the like. 5 The outlet flue from the furnace A is indicated at 11. Heat transfer is had to the rooms B by conduits 12 while a return conduit 13 is in association with the said rooms. The communicative points of the conduits 12 and 13 with the rooms B are equipped with registers, generally indicated at 14. These conduits 12 and 13 are a part of a casing 15 in which is located a water radiator 16 of the tube type.

Within the furnace A above its firebox (not 15 shown) is a pipe coil 17 having the end 18 opening into the top portion of a pressure water tank 19 while the other end 20 of this coil opens into the said tank 19 adjacent the bottom, the tank being vertically disposed and supported in 20 any suitable manner. The upper portion of the said tank 19 effects a steam dome 21, the steam being generated by the coil 17 in the working of the furnace A. This steam dome has common thereto a steam pressure gauge 22, release valve 25 22', water glass 23' and oil cup 24'. Water is admitted to the tank 19 from a water supply pipe 23 which opens into the large hot water tank 56 and communicates therewith the tank 19 through pipes 57 and 58 and its point 30 of communication has associated therewith a float-operated cut-off valve 24. The pipe 23 is provided with a hand-operated cut-off valve 25. Hot water for domestic use is drawn from the hot water tank 56 through pipe 64 where it is 35 discharged through the faucet 65.

Leading from the water jacket 10 of the furnace A is a water pipe 26 which opens into the radiator 16 and interposed intermediate thereof is a manually-operated cut-off valve 26'. Connected to the pipe 26 between the valve 26' and the water jacket 10 is a water pipe 59 which communicates at its other end with the hot water tank 56 adjacent its top. The pipe 57 leads from the lower portion of the tank 56 to 45 the bottom portion of the heating jacket 10 to effect circulation of hot water between the tank 56 and the heating jacket 10. Projecting from the radiator 16 and provided with the cut-off valve 62 is a water disposal pipe 63 for use when 50 my invention is to be used as a cooling unit.

Arranged on a suitable support or stand 27 is a gear housing 28 which has built therewith at one side a steam cylinder 29 in which is reciprocatingly mounted a piston 30, its stem 31 being 55

slidable in a bearing 32 on the housing 28. This cylinder is built with a steam chest 33 in which works a slide valve (not shown) for regulating the exhaust and supply of steam alternately at opposite sides of the piston 30 within and from the cylinder 29. Steam from the dome 21 is delivered or admitted to the steam chest 33 by a lead pipe 34, the exhaust from the said chest being effected in any desirable manner.

10 Bracketed above the housing 28 is the driving shaft 35 of a draft fan 36, which is of the bladed type. This drive shaft 35 is equipped with a belt pulley 37 having trained thereover an endless belt 38 which is also trained over a belt pulley 39 fixed to a driven shaft 40 journaled transversely in the housing 28. The fan 36 is within the casing 15 and is in confronting relation to the radiator 16 at the entrance of the return conduit 13 to the said casing 15. Thus the spent heated air returned through the conduit 13 is blasted through the radiator 16 for the reheating of this air and the transfer thereof through conduits 12 into the rooms B where such air will circulate and again return through conduit 13. The radiator 16 heats the air and such heating is continuous in the circulation of air through the system.

The driven shaft 40 has thereon a pinion 41 meshing with a gear 42, which is in association with a gear 43. The gear 43 meshes with gears 44 and 45, respectively, these being loose on a shaft 46 common thereto and such gears 44 and 45 are at opposite sides of the gear 43. Shiftable on the shaft 46 is a double clutch 47 for alternately engaging the said gears 44 and 45, the clutch 47 being splined to the said shaft 46 for sliding movement. The shaft 46 has fixed thereto a rack gear 48 meshing with a toothed rack 49 formed on the stem 31 of the piston 30.

40 The control 50 for the valve (not shown) within the steam chest, which is of any conventional form and is synchronized properly for the working of said valve, actuates a bell crank lever 51, which has connection with the clutch 47, so that on reciprocation of the stem 31 of the piston 30 in the working of the steam engine the said clutch 47 will be alternately clutched with the gears 44 and 45 thereby effecting a continuous drive in one direction to the shaft 40 during reciprocation of the piston 30 within the cylinder 29.

45 The shaft 40 operates a rotary water pump 52 which has the lead pipe 53 to the radiator 16 and the lead pipe 54 to the pipe 57. The pipe 57 joins the pipe 54 with the water jacket 10, and in this manner water circulation is assured through the radiator 16 in the water flow system of the apparatus. The pipe 54 is provided with a cut-off valve 54' and intermediate the water pump 52 and the cut-off valve 54' is connected a cooling unit pipe 60 which connects at its other end to the water supply pipe 23. The pipe 60 is provided with a cut-off valve 61.

50 The gears 41, 42, 44, 45 and clutch 47 are confined within the housing 28, the shafts 40 and 46 being suitably journaled therein. The pump 52 is suitably bracketed at 55 to the housing 28 at one side thereof preferably beneath the cylinder 29 having the reciprocating piston 30 therein.

55 When my invention is used as a heating unit, water is introduced into the unit from the supply pipe 23 and into the water jacket of the furnace A where it is heated. Water is also introduced into the pressure water tank 19 and heat-

ed in the coil 17. The steam within the steam dome 21 of the tank 19 enters the steam chest 33 through the pipe 34 to actuate the piston 30 which, in turn, operates the fan actuating mechanism mounted within the housing 28, in the manner hereinbefore described. The steam may be exhausted from the steam chest 33 in any suitable manner. Water is drawn from the water jacket 10 of the furnace and circulated through the pipe 26, radiator 16 and pipe 53 to the pump 52 and, from the pump, the water is forced back into the water jacket 10 through the pipes 54 and 57 to be reheated. Valves 61 and 62 in pipes 60 and 63, respectively, are closed and valves 26' and 54' in pipes 26 and 54, respectively, are opened permitting the hot water from the water jacket 10 to circulate through the radiator 16 where the fan 36 blasts the spent air from the return conduit 13 through the radiator where it is reheated and forced back into the rooms B through conduits 12.

60 When my invention is to be used as a cooling unit, valves 26' and 54' in the pipes 26 and 54, respectively, are closed and valves 61 and 62 in pipes 60 and 63, respectively, are opened permitting the cool water from the supply pipe 23 to pass through the pipe 60, through the pump 52, and into the radiator 16 where it is discharged through the pipe 63, the fan 36 will then blast the spent air entering through the conduit 13 through the radiator 16 and the cooled air issuing therefrom will be forced into the rooms B through the conduits 12. The pump 52 is operated in the manner hereinbefore described, and the hot water for domestic use is heated in the water jacket 10 of the furnace and obtained from the hot water supply tank 56.

65 It is to be understood that the form of my invention, herewith shown and described, is to be taken as a preferred example of the same, and that various changes in the size, shape and arrangement of parts may be resorted to without departing from the spirit of my invention or the scope of the appended claims.

70 What is claimed is:

1. A heating apparatus for association with a furnace having a water jacket, comprising the combination of distributing conduits and a return conduit communicating with the enclosures to be heated, a casing having the conduits communicating therewith, a water radiator within said casing, a supply conduit connection between the radiator and the water jacket of the furnace, a water tank adapted to be partially filled with water and the portion thereof above the water comprising a steam dome, a supply conduit for introducing water into the said water tank, a heating coil within the furnace and communicative with said tank, a steam engine, a conduit connecting the steam engine with the steam dome of the water tank, a water pump operated by said engine and communicative with the radiator and said tank for effecting circulation of heated water through the radiator, and a draft fan operated by said steam engine and arranged within said casing in confronting relation to the said radiator intermediate the radiator and the return conduit to force the cooled air from the return conduit through the radiator and into the said distributing conduits.

75 2. A heating apparatus for association with a furnace having a water jacket, comprising the combination of distributing conduits and a return conduit communicating with the enclosures to be heated, a casing having the conduits com-

- 5 municating therewith, a heat exchanger disposed within said casing and communicative with the water jacket of the said furnace, a water tank adapted to be partially filled with water and the portion thereof above the water comprising a steam dome, a supply conduit for introducing water into the said water tank, a heating coil within the furnace and communicative with said tank, a steam engine having a reciprocating rack, 5 a conduit connecting the steam engine with the steam dome of the water tank, a gear housing associated with the steam engine, gear means mounted within said housing and actuated by the rack, a water pump operated by said gear 10 means and communicative with the heat exchanger and said tank for effecting circulation of heated water through the heat exchanger, a draft fan actuated by the said gear means and arranged within said casing in confronting relation to the said heat exchanger intermediate the heat exchanger and the return conduit to force the cooled air from the return conduit through the heat exchanger and into the said 15 distributing conduits. 20
- 25 3. A heating apparatus for association with a furnace having a water jacket, comprising the combination of distributing conduits and a return conduit communicating with the enclosures to be heated, a casing having the conduits communicating therewith, a water radiator within said casing, a supply conduit connection between the radiator and the water jacket of the furnace, a water tank adapted to be partially filled with water and the portion thereof above the water 30 comprising a steam dome, a supply conduit for introducing water into the same water tank, a heating coil within the furnace and communicative with said tank, a steam engine, a supply conduit connecting the steam engine with the steam dome of the water tank, a water pump operated by said engine and communicative with the radiator and said tank for effecting circulation of heated water through the radiator, a draft fan actuated by the steam engine arranged 35 within said casing intermediate the radiator and the return conduit in confronting relation to the said radiator to force cool air from the return conduit therethrough and into the distributing conduits, means for feeding water to the tank, and valve means within the tank for controlling the supply of water thereto. 40
- 45 4. A heating apparatus for association with a furnace having a water jacket, comprising the combination of distributing conduits and a return conduit communicating with the enclosures to be heated, a casing having the conduits communicating therewith, a water radiator within said casing, a supply conduit connection between the radiator and the water jacket of the furnace, 50 a water tank adapted to be partially filled with water and the portion thereof above the water comprising a steam dome, a heating coil within the furnace and communicative with said tank, a steam engine having a reciprocating rack, a supply conduit connecting the steam engine with the steam dome of the water tank, a gear housing associated with the steam engine, gear means mounted within said housing actuated by the reciprocating rack, a water pump operated by said gear means and communicative with the radiator and said tank for effecting circulation of heated water through the radiator, a draft fan actuated by the said gear means and arranged within said casing intermediate the radiator and the return conduit and in confronting relation to the said radiator to blast cooled air from the return conduit through the radiator and into the distributing conduits, means for feeding water to the tank, a valve means within the water tank to automatically control the supply of water thereto, a manual cut-off in said means, and a clutch mechanism operated by the reciprocating rack of the steam engine and automatically cooperative with the gear means for effecting continuous drive of the fan and pump in one direction. 55

MARSHALL ARTER.
